UNITED STATES PATENT OFFICE.

JAMES W. WALLS, OF TRINIDAD, COLORADO.

SWITCH-FROG.

No. 909,351.

Specification of Letters Patent.

Patented Jan. 12, 1909.

Application filed July 20, 1908. Serial No. 444,443.

To all whom it may concern:

Be it known that I, JAMES W. WALLS, citizen of the United States, residing at Trinidad, county of Las Animas, and State of Colorado, have invented certain new and useful Improvements in Switch-Frogs, of which the following is a specification, reference being had therein to the accompanying drawing.

- 10 This invention relates to a switch frog and particularly to a pivotal mounting thereof. The invention has for an object to provide a novel and improved construction of pivotal mounting for the movable rail stub 15 switch frog by which a firm bearing for the frog rail is obtained and the limit of travel thereof positively determined so as to insure safety and accurate alinement as the frog is shifted.
- 20 Other and further objects and advantages will be hereinafter fully set forth and the novel features of the invention defined by the appended claims.

In the drawing:—Figure 1 is a plan showing the application of the invention and its connections; Fig. 2 is a plan of the frog; Fig. 3 is a longitudinal section thereof, Fig. 4 is a section on line 4—4 Fig. 2, and Fig. 5 is a section on line 5—5 Fig. 2.

30 Like numerals refer to like parts in the several views of the drawing.

The numeral 10 designates the main line rails which are supported on ties in the usual manner, and 11 the switch rails also 35 mounted in the usual manner. The free end of one of the switch rails is provided with a throw rail 12, and the opposite main line rail is provided with the throw rail 13, these being connected together by the shifting bar 14 in the usual manner to be simultaneously moved by any desired connections, for instance, the switch stand at 15. The bar 14 is connected to one arm of the bell crank or angle lever 16 which is pivotally mounted at 17, and the opposite arm thereof connected to the shifting rod 18 extending to the frog connection. The connection of the bar 14 and the shifting rod 18 with the crank lever 16 is by means of a 40 pivotal joint of any desired character. The rod 18 is pivotally connected at 19 with the arm 20 of the T lever 21 which is pivoted at 22. Each of the lateral arms of this T lever is attached to the frog by means of the connections 23 so as to shift both ends thereof 45 simultaneously in opposite directions.

The frog rail 25 is mounted upon a base plate 26 firmly supported upon the ties and secured thereto. This base plate is provided with a central circular depression or pivoting seat 27 and at each end is formed with the flange 28 disposed beneath the adjacent track rails so as to provide a firm bearing at the point of alinement with the frog. The base plate is also provided with 50 ear lugs 29 above this flange to engage the flanges of the track rails and firmly support them against lateral movement upon the plate 26. Disposed upon the upper face of the plate 26 is the rail plate 30 which extends longitudinally thereof and is provided at 55 its midlength with a curved pivoting depression 31 seated in the depression 27 of the base plate so as to form a broad, firm pivotal bearing beneath the longitudinal center of the frog rail 25. At each end of the rail plate 30 depending lugs 32 extend through apertures 33 in the base plate and are attached to the connections 23 for shifting the frog. The rail 25 is bolted or otherwise secured to the plate 30, and the travel of this plate is positively limited by the extent of the apertures 33 through which the throw lugs 32 extend. For the purpose of preventing any vertical movement or play of 60 the rail plate upon its base a cross strap 34 is provided and extends laterally of the base plate and rail plate, being deflected at 35 to pass beneath the rail and permit the oscillatory movement of the rail plate upon the 65 base, while preventing any vertical movement thereof. This cross strap is attached to the base by any desired means, as at 36 and also to the tie or foundation at 37 so as to assist in retaining the base plate upon its 70 foundation.

For the purpose of controlling a derailer 38 in the switch track, a connection 39 extends from one of the lugs carried by the frog rail to a bell crank 40 suitably mounted and connected by rod 41 to a bell crank 42 for the derailer so that when the frog is in alinement with the main line the derailer is open, as shown in Fig. 1, and will be automatically closed when the frog is shifted to the switch 45 track.

In the operation of the invention, it will be seen that when the throw rails are shifted the frog is also thrown upon its pivot to connect with the switch track and the derailer 50 therein closed, while when the parts are in main line connection, as shown in Fig. 1, the

- derailer upon the switch is open and the throw points disposed in alinement for the main line. The mounting for the frog provides the solid iron base with a broad pivot 5 for the rail plate and supports for the connecting rails so that the parts are retained in alinement, while the travel of the frog stub is positively governed thus insuring safety and accuracy in the shifting thereof.
- 10 The base plate for the frog and the rail plate therefor are held against vertical movement by means of the cross bar so that the invention presents an efficient and economically constructed form of safety switch having an 15 automatically operated frog and derailer in connection therewith.
- Having described my invention and set forth its merits, what I claim and desire to secure by Letters Patent is:—
- 20 1. In a switch frog, a base plate having a central concave depression and horizontal end portions, a rail plate provided with a central circular depression pivoted in the depression of the base plate, and with end 25 portions resting upon those of the base, and means for shifting said rail plate.
2. In a switch frog, a base plate having a central circular depression, a rail plate provided with a central circular depression pivoted in the depression of the base plate, and depending lugs from the opposite ends of said rail plate extended through slots in the base plate.
3. In a switch frog, a base plate having a central circular depression, a rail plate provided with a central circular depression pivoted in the depression of the base plate, and a cross bar extended into the depression of the rail plate and secured at its opposite 40 ends to the base plate.
4. In a switch frog, a flat base plate provided with a central pivoting depression below the level of the adjacent end portions and rail supporting flanges at the opposite ends thereof, a rail plate provided with a frog rail and pivotally mounted upon said base.
- 45 5. In a switch frog, a base plate provided with a central pivoting depression and rail supporting flanges at the opposite ends thereof, a rail plate provided with a frog rail and pivotally mounted upon said base, and holding lugs extended from the base to engage the rails supported upon the flanges.
6. In a switch frog, a base plate provided with a central pivoting depression and rail supporting flanges at the opposite ends thereof, a rail plate provided with a frog rail and pivotally mounted upon said base, holding lugs extended from the base to engage the rails supported upon the flanges, and depending lugs from said rail plate extending through slots in the base plate.
7. In a switch frog, a base plate provided with a central pivoting depression and rail supporting flanges at the opposite ends thereof, a rail plate provided with a frog rail and pivotally mounted upon said base, holding lugs extended from the base to engage the rails supported upon the flanges, depending lugs from said rail plate extending through slots in the base plate, a cross bar depressed beneath the rail at the pivotal center of the rail plate, means for securing said bar to the base plate, and means at the free ends of said bar for securing the base plate to a support.
8. In a switch, a switch frog comprising a pivoted rail plate having lugs at its opposite ends, an operating lever having connections with each of said lugs, a derailer, and a rod extending from one of said lugs and having operating connections with said derailer.
9. In a switch, a switch stand, throw points connected therewith, a T-lever connected for operation in unison with said throw points, a switch frog comprising a pivoted rail plate having lugs at its opposite ends, connections from the arms of the T-lever to said lugs, a derailer, and a rod extending from one of said lugs and having operating connections with said derailer.
- In testimony whereof I affix my signature in presence of two witnesses.
- JAMES W. WALLS.
